UNITED STATES PATENT OFFICE.

NATHAN M. RUTHSTEIN, OF RACINE, WISCONSIN, ASSIGNOR TO STEEL SHOE COMPANY, OF RACINE, WISCONSIN, A CORPORATION OF WISCONSIN.

FOOTWEAR.

1,026,407.

Specification of Letters Patent. Patented May 14, 1912.

Application filed December 21, 1908. Serial No. 468,457.

To all whom it may concern:

Be it known that I, NATHAN M. RUTHSTEIN, a citizen of the United States, residing at Racine, in the county of Racine and State of Wisconsin, have invented certain new and useful Improvements in Footwear, of which the following is a specification, reference being had therein to the accompanying drawing.

10 My invention relates to improvements in boots, shoes and similar articles of footwear and has particular reference to that class of footwear in which the sole and heel are constructed of sheet-metal.

15 The object of the invention is to provide a construction in articles of the character specified whereby the knobs or spurs or bosses on the under face of the sole and heel may be replaced and renewed at any time.

20 With this object in view the invention comprises the matters hereinafter set forth and then recited in the appended claims.

In the accompanying drawing which illustrates practical embodiments of the several features of my invention, Figure 1 is a perspective view of a shoe illustrating my present improvements, parts being broken away for clearness of illustration; Fig. 2 is a bottom plan view of the shoe shown in Fig. 1; Fig. 3 is a detail plan view of the vamp shown in Fig. 1; Fig. 4 is a sectional view of the construction shown in Fig. 2; and Fig. 5 is a sectional view illustrating a modified form of construction.

35 Referring to the drawing, the bottom of the shoe is made of sheet-metal stamped up in a die to form the sole 5, hollow heel 6, shank 7, the latter being suitably curved, and the upstanding marginal flange 8, the size and outline of these parts varying with different dimensions of the finished boots or shoes. The sole and heel portions are provided with knobs or bosses 9 and in order to carry out one of the objects of this invention,

40 I provide a structure whereby these knobs may be readily removed and replaced or renewed as they become worn. This may be accomplished in a variety of ways, but the simplest and most convenient as well as

45 effective manner of doing it, is to provide the sheet-metal of the bottom with a number of holes or perforations having the circumferential metal upset or turned inwardly as shown at 10 to form more extended bearings than would be provided merely by the

thickness of the metal, the bearings being provided with interior screw threads in order to make a threaded engagement with the corresponding screw threads on the shanks 11 of the knobs as clearly shown in Fig. 4. It is obvious that by this arrangement the knobs may be secured in place in an easy and convenient manner, and when worn they may be removed and new ones put in place. As the wear of shoes or boots of this general character occurs in the main upon the knobs or other projections with which the bottoms are provided, the provision of renewable or replaceable knobs prolongs the life of the boot or shoe indefinitely as the wearer may himself make the replacements or renewals at comparatively insignificant cost and without returning the shoe to the factory. The heads of the knobs are provided with suitably squared or other shaped portions 12 adapted to receive a correspondingly shaped wrench or tool by which the threaded engagement and disengagement of the shanks and bearings may be effected.

50 In shoes or boots of this general type the bottom is usually made of a sheet of thin metal, usually sheet-steel, which is not of sufficient thickness to afford a substantial and sufficiently extended bearing for the shanks of the knobs, and the material for such bearings as are necessary to provide secure fastenings is readily obtained by the means above described. This could be effected by any other suitable means; for example, a supplemental strip or piece of metal 13 could be employed extending along the line or lines of the holes and adapted to make threaded engagement with the knobs. I prefer the form in which the metal is struck up as illustrated in Fig. 4 as this may be provided and made at the same time the bottom is struck up to shape and without employing any excess metal.

55 Boots or shoes of this kind are usually provided with a reinforcing strip 14 of leather or other suitable material extending around the margin of the vamp, quarter, and counter as shown in Fig. 1. Rivets 15 pass through the flange, reinforce strip and material of the shoe or boot to secure the parts together, and the reinforce extends above the edge of the flange and fits within its contour, standing vertically in place against the inner face thereof. The vamp

16 is curved at the toe to fit the curved toe portion of the flange, and in the manufacture of these shoes as heretofore practised it has been necessary to "last" the vamp in 5 order to take up the excess or fullness of material at the toe produced by the vertical or downturned skirt 17 of the vamp. This "lasting" process is expensive and consumes much time; I obviate this objectionable "lasting" by providing the skirt of the toe portion of the vamp with a series 10 of slits 18 which allow the excess or fullness of material to be taken up when the vamp is assembled in place. This is clearly 15 shown in Figs. 1 and 3.

It is of course understood that the heel portion may be filled in any suitable manner and that suitable insoles and linings 20 may be employed, these being now well known in the art and forming no part of the present invention.

Having described my invention what I claim is:—

1. In a device of the class described, a 25 shoe having a sheet-metal bottom comprising the sole and heel and having a plurality of perforations, the metal around the perforations providing inwardly extending

screw-threaded bearings, and a series of knobs having screw-threaded shanks in 30 threaded engagement with the bearings for engagement and disengagement therewith from the outside of the shoe.

2. A shoe bottom formed of drawn sheet metal and having openings in its lower side, 35 the metal at the edge of each opening being bent inwardly or upwardly out of the plane of the body of the metal to form an angular flange surrounding the opening, said flange and opening being screw-threaded, and a stud having a screw-threaded shank engaging with the screw-threads of said flange and opening, the head of said stud being of greater diameter than said shank and having a tapering lower end and a wrench face, 40 said head and said flange lying at opposite sides of the metal, said head being turned into water-tight contact with the lower or outer surface of the metal.

In testimony whereof I affix my signature 45 in presence of two witnesses.

NATHAN M. RUTHSTEIN.
